UNITED STATES PATENT OFFICE

2,428,626

BOOT CONSTRUCTION

Edward V. Jaeger, Denville, N. J., and Ralph M. Plympton, Yarmouth, Maine, assignors to R. C. Nichols Corporation, Yarmouth, Maine, a corporation of Maine

Application August 3, 1946, Serial No. 683,222

3 Claims. (Cl. 36—4)

1

This invention relates to a boot construction, and, more particularly, to that type of hunting boot having a rubber foot section and a leather, upper section fitting over the lower portion of the leg.

One of the objects of this invention is to provide a simple, practical, durable and economical boot construction. Another object is to provide a construction of the above character in which the maximum of comfort is attained without sacrificing the durability of the boot. Another object is to provide a construction of the above character in which the boot may be unusually comfortable without increasing the cost of manufacture. Other objects will be in part obvious and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings, in which is shown one of the various possible embodiments of this invention,

Figure 1 is a perspective of a boot having the features of our invention embodied therein;

Figure 2 is a fragmentary, longitudinal section taken along the line 2—2 of Figure 1; and,

Figure 3 is a rear view of the same type of boot shown in Figures 1 and 2, but having another embodiment of our invention incorporated therein.

Similar reference characters refer to similar parts throughout the several views of the drawings.

Referring now to Figure 1 in which is shown the preferred embodiment of this invention, there is a lower, rubber section generally indicated at 10, shaped to fit about the foot of the wearer. An upper, leather section, generally indicated at 11, is secured to lower section 10 as by stitching generally indicated at 12. The boot is in the general form of a hunting boot having a tongue 13, the usual lacing generally indicated at 14, and a boot strap 15, all of conventional construction. At the bottom of the upper boot section 11 the lacing margins come together in abutting relationship so that the lower margin of the upper boot section and stitching 12 extend continuously across the vamp of the boot, and in fact extend around the entire upper margin of the lower boot section.

In boots of this type now in use, there is a ridge or irregularity formed along the interior surface of the boot adjacent the heel of the wearer. This irregularity is caused by the seam or junction of

2

the upper, leather section and the lower, rubber section. Further irregularities may occur after use, for the leather section has a tendency to wrinkle. Where such boots are worn constantly, the boot tends to slide somewhat along the heel and back of the leg of the wearer, and this ridge or irregularity irritates the skin surface causing blisters or other types of sores. It is an object of this invention to eliminate these difficulties.

10 The rear portion 16 of the lower, rubber section 10, as best seen in Figure 2, extends upwardly to a point above the heel of the wearer and the counter portion with the upper edge 16a being substantially at ankle height adjacent the lower portion of the leg. Thus the edge 16a of this rear portion 16, as well as the stitches 12, are spaced above the heel of the wearer and do not engage the heel when the boot is worn. This edge which forms an irregularity in the interior 20 surface of the boot thus is located on the upper section of the boot where there is practically no relative movement between the boot and the leg of the wearer. The top or upper edge 16a of rear portion 16 is curved forwardly and downwardly to the side wall portions where it is connected thereto with this upper edge merging with the upper edges of the side wall portions at a level which is substantially that of the top of the vamp of the boot. The side wall portions are connected 25 to the vamp portion with the upper edge extending upwardly and thence at a higher level over the central portion of the vamp. The entire lower boot section being of rubber does not wrinkle and tends to return to its original configuration at any 30 time that it is deformed. The construction is such that a snug fit is attained while at the same time the upper edge 16a is urged somewhat to the rear away from the foot of the wearer. That is, when the boot is being laced up and the lacing 35 margins are drawn together, the side walls of the upper boot section 11 transmit forces to the lower boot section which tend to draw the rear side wall portions of the lower boot section in against the sides of the foot. In this way the flexible 40 and yet firm rubber walls tend to maintain an un-wrinkled condition and the upper rear edge is arched rearwardly away from the heel of the wearer so that the pressure is relieved at edge 16a at the rear of the boot. Consequently, with the 45 only irregularity in position above the heel and leather wrinkles avoided, there can be no irritating effect when the boot is worn.

In the embodiment shown in Figure 3, the lower section 10 has a rear, upwardly extending portion 10a terminating at the top of the boot. The

upper section 11 of the boot is divided into two portions 11a and 11b, which are stitched to the lower section 10 along the border thereof. Accordingly, as shown in Figure 3, sections 11a and 11b are secured by stitching to the upwardly extending portion 10a of the section 10. In this manner, there is no leather to wrinkle nor is there any ridge or irregularity in the rear portion of the boot and particularly at the heel portion, and accordingly, irritation to the heel of the wearer is avoided.

Accordingly, the various objects of this invention have been achieved in a practical manner in the structure described above.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

What is claimed is:

1. In a boot construction, the combination of, a lower boot section formed of rubber or like material and having a peripheral wall construction which includes low side wall portions, a rear wall portion, and a vamp portion, said rear wall portion having its upper edge extending to substantially ankle level above the counter portion thereof and curving forwardly and downwardly to the side wall portions where said side and rear wall portions are connected with said upper edge of the rear wall portion merging with the upper edges of said side wall portions at a level which is substantially that of the top of the vamp of the boot, and an upper boot section formed of leather or like material and shaped to fit about the ankle and calf of the wearer and having a bottom edge which is attached to the top edge of the lower boot section with the adjacent edge portions of the two sections being substantially parallel throughout and with said upper boot section terminating at its connecting margin with said lower boot section, said upper boot section having its side portions terminating at the front thereof in lacing margins, whereby, upon said lacing margins being drawn together, the side walls of said upper boot section are pulled snugly around the foot and lower leg of the wearer with the pulling action thereof being transmitted to the lower boot section, and whereby the lower boot section is pulled generally against the foot and pressure is relieved at the rear of said bottom section above the counter portion.

2. In a boot construction, the combination of: a one-piece lower boot section formed of rubber or like flexible material, said lower boot section having a heel and sole construction and a peripheral wall construction which includes low side wall portions, a rear wall portion, and a vamp portion, said rear wall portion having its upper edge extending to substantially ankle level above the counter portion thereof and curving forwardly and downwardly to the side wall portions where it is connected thereto with its upper edge merging with the upper edge of said side wall portions at a level which is substantially that of the top of the vamp of the boot; and an upper boot section formed of leather or like material and shaped to fit about the lower leg of the wearer

and having a bottom edge which is attached to the top edge of the lower boot section with the adjacent edge portions of the two sections being substantially parallel throughout and said upper boot section terminating in a lower margin which overlaps and is stitched to said lower boot section, said upper boot section having its side portions terminating at the front thereof in lacing margins, said lacing margins approaching and meeting each other at the vamp of the boot so that said lower margin of the upper boot section extends continuously across the vamp; whereby, upon said lacing margins being drawn together, the side walls of said upper boot section are pulled snugly around the foot and lower leg of the wearer with the pulling action thereof being transmitted to the lower boot section, and the lower boot section is pulled generally against the foot and the rear of said bottom section is arched rearwardly above the counter portion thereof.

3. In a boot construction, the combination of, a lower one-piece boot section formed of rubber or like material and having a heel and sole portion and a peripheral wall construction which includes low side wall portions, a rear wall portion, and a vamp portion, said rear wall portion having its upper edge extending to substantially ankle level above the counter portion thereof and curving forwardly and downwardly to the side wall portions where said side and rear wall portions are connected with said upper edge of the rear wall portion merging with the upper edges of said side wall portions at a level which is substantially that of the top of the vamp of the boot, said upper edges extending upwardly at the top of said vamp portion and joining at a level which is higher than the upper edges of said side wall portions, and an upper boot section formed of leather or like material and shaped to fit about the ankle and lower leg of the wearer and having a bottom edge which is attached to the top edge of the lower boot section with the adjacent edge portions of the two sections being substantially parallel throughout and with said upper boot section terminating at its connecting margin with said lower boot section, said upper boot section having its side portions terminating at the front thereof in lacing margins.
